UNITED STATES PATENT OFFICE.

ANTON MAZZANOVICH, OF LOS ANGELES, CALIFORNIA.

THEATRICAL COUNTERWEIGHT SYSTEM.

Application filed March 15, 1923. Serial No. 625,194.

To all whom it may concern:

Be it known that I, ANTON MAZZANOVICH, a citizen of the United States, residing at Los Angeles, in the county of Los Angeles 5 and State of California, have invented new and useful Improvements in Theatrical Counterweight Systems, of which the following is a specification.

This invention relates to stage paraphernalia and more particularly to drop, flat and ceiling counterweight systems.

It is an object of the present invention to provide an improved counterweight system for facilitating the erection and knocking down of theatrical sets. It is an object to provide an apparatus practically operative with a minimum of manual labor. Another object is to provide a counterweight system in which suspended counterweights can be accurately adjusted to substantially counterbalance theatrical elements to be erected or handled on a stage. Another object is to provide means for conveniently retracting systems of drop ropes and cables so that they may be maintained in an out-of-the-way position to give head room. Another object of the invention is to provide counterweight and lift lines which may be conveniently operated from a fly floor or from the stage without necessitating the ascent of a flyman into the rigging lofts.

Other objects and advantages will be made manifest in the following specification of an embodiment of the invention illustrated in the accompanying drawings, wherein

Figure 1 is a vertical section and elevation showing a preferred adaptation of the invention.

Fig. 2 is a perspective of one of the counterweight hoppers.

Fig. 3 is a detail view showing a trim cable clamp attached to a trim cable.

Fig. 4 is a view showing a spot line baton.

Fig. 5 is a vertical section and elevation showing a ceiling drop system.

Fig. 6 is a diagrammatic view showing the system as adapted for retracting the lifting cables.

Fig. 7 is a detail of one of the hopper discharge valves.

The present invention consists of a counterbalance rope and cable system of which any number of sets of ropes may be employed as in the usual manner in successive lines to facilitate the raising and lower-

ing of various theatrical stage fixtures, one of which is shown in Figure 1 as including a drop D along the upper portion of which extends a baton B. In my invention a number of suitable clamps 2 are adapted to be attached to the baton of a drop or flat and from these clamps extend respective cables. A center counterweight cable 3 is attached to the center clamp of the baton and is led up over a guide pulley 4 and thence to a lateral guide pulley 5 down to a floating counterbalance which, in the preferred form, consists of a hopper 6 of suitable dimensions. The hopper is adapted for vertical guided movement and is shown as provided with perforated ears 7 at each side to receive tight guides or wires 8 fastened at the top and bottom and in suitable spaced relation. Preferably, there is introduced in the counterweight cable 3 a turn buckle 9 providing for close adjustment of the apparatus.

For nicely trimming the drop D the clamps at the ends of the baton B are attached to contiguous ends of a cable 10 which has a bight 10^a passing over lateral guide pulleys 11 and thence down to the counterweight 6, which is provided with bight pulleys 12. These pulleys are shown as supported in a cross bar 13 provided at the upper end of the hopper 6, which has an eye 14 to receive a hook 15 of the cable 3, as clearly shown in Figure 2.

A feature of the invention is to provide for the close counterbalance of the different flats and drops, and since these may vary greatly in weight I prefer to use a counterweight including the hopper 6 and a mobile charge therein in the nature of shot S, Figure 7, of which a suitable quantity can be introduced into each of the hoppers, according to the weight of the element to be counterbalanced thereby.

In order to facilitate the ready transfer and removal of a portion of the shot charge from a hopper, the bottom of the hopper is provided with a discharge valve 6^a which may be opened as necessary and a portion of the shot run out. This enables the ready transfer of the shot from one hopper to another of a series by the application of a simple trough to the discharge of one hopper, the opposite end of the trough being disposed upon the open upper end or mouth of another hopper which is to be further weighted. Such a form of transfer trough

is indicated in longitudinal section at T in Figure 7; one end of the trough being adapted for attachment as to the stem of the valve 6^a. Thus, to transfer shot from one hopper to another it is only necessary to apply the trough T and to open the valve 6^a and permit the shot to flow from one hopper to the other.

While a given counterbalance hopper is in elevated position it is adapted to be secured against descending movement as by a block and tackle including a rope 17, one block 18 of the tackle being connected to the fly framework, as shown in Figure 6, while the lower block is adapted to be connected to a ring 19 provided on the cross bar 13 of a hopper, as shown in Figure 2, and when thus tackled up the tackle rope 17 can be belayed as by a few wraps around a cleat 20. When a counterweight is so hung up, as shown in Figure 6, the cables 3 and 10 can be retracted to an out-of-the-way, overhead position until required for handling a drop of flat, and to so pull the cables out of the way I provide a lift line or rope 22 which may be connected as to the central baton clamp. The lift line or rope 22 extends upwardly over loft pulleys 23 and thence down at the stage side to a cleat 24 over which the flyman belays the rope 22 after he has pulled up the cables 3—10, as is clearly shown in Figure 6.

When it is desired to set up a flat or drop the flyman lets out the lift rope 22 and this permits the cables 3—10 to descend and allows their clamps 2 to be applied as to a baton B of a drop or flat. The flymen then release the block and tackle rope 17 from the cleat 20 with the result that the counterweight 6 becomes operative to counterbalance the attached stage flat or drop and the latter can be raised to a vertical position over the stage, as is clearly shown in Figure 6.

When a flat or drop D is thus connected to its cables 3 and 10, the side cables 10 compensate by the shifting of the bight around their pulleys 12 in the head of the counterweight and the drop becomes nicely trimmed or positioned and the trimming line or cable 10 may then be clamped to prevent further shifting as by means of a clamp 25, Figure 8, which can be closed about a contiguous portion of the trimming cable 10 while the clamp is attached as to the cross bar 13 of the counterweight. This prevents a sliding or shifting of the trimming cable 10 as to the counterweight and operates to hold the attached flat or drop D properly positioned.

The flat or drop can be readily raised vertically out of the way above the stage to the dotted line position, Figure 1, by means of the lift line 22. During the lifting of a drop D the trimming cable 10 is slackened

and the counterweight received in its bight is lowered down the guide wires 8, Figure 1. To again lower the elevated drop D, the flyman hauls down on a counterweight lift rope 26 which serves to pull the counterweight upwardly and lower the drop.

After a scene has been set up it is sometimes desirable to lower a ceiling C into position on the top of the flats and sometimes the ceilings will overhang or project beyond the tops of the flats. In such cases the flats are clamped in stable condition and then the counterweights are pulled up sufficiently to provide for slackening off of cables as 3 and 10 to permit a ceiling C to be lowered down on top of the flats without interference of the cables which otherwise are taut.

In Figure 5 the ceiling C is indicated as being connected to counterweight cable ends 10 and to the cable 3. It is sometimes desirable to convex the ceiling so as to provide for the introduction or application of a "border light" and this I provide for by suspending the edges of the ceiling from the cable ends 10 and pulling up on the center of the ceiling as by an applied lift-rope 22, Figure 5, which may be adapted to the clamp 2 of the cable 3. By pulling up on the lift rope 22 tension is relieved from the cable 3 and this is slackened off as is indicated. The bowed ceiling is sustained by belaying the lift rope 22 around its cleat 24 while the edges of the ceiling are either suspended by the cable ends 10 or may rest upon the top of the said flats. A border light L is indicated as being applied under the bowed ceiling C.

It is understood that various elements of stage paraphernalia may be readily handled and counterpoised by the present system, and in Figure 4 there is shown a spot line baton B' having eyes 29 to which the spot lines may be attached while the baton B' is suspended by the cables 3 and 10 above described.

It will be seen that in dismantling a setting, the counterbalances of the several flats, drops and other elements can be hauled up to lower the elements flat down upon the floor or stage and while so hauled the counterbalances are adapted to be hung up as is shown in Figure 6 until further use is required. As fast as the elements are disconnected from the cable clamps the cables and the clamps are pulled up to an overhead, clear position.

One of the important advantages of my present invention is that a great deal of manual labor on the part of the flymen in handling counterweights and counterweight sections is wholly eliminated, since, by my improvement, it is possible to transfer the fluid counterweight medium, such as shot, from one hopper to another without manual effort. It is understood that any suitable

mobile medium, such as sand or water, may be utilized in place of shot.

Further embodiments, modifications and variations may be resorted to within the principle of the invention.

What is claimed is:

1. In a theatrical counterweight system, means forming vertical parallel guides, a hopper mounted to move vertically upon the guides, a cross bar connected to the hopper, pulleys mounted upon the cross bar, a baton, an adjustable counterbalancing cable connected to the center of the baton and running over guide pulleys and downwardly and connected to the cross bar, a second equalizing cable connected at its ends to the ends of the baton and running over guide pulleys and around the pulleys upon the cross bar, and valve means for adjusting the weight of the hopper to counter-balance the load carried by the baton. 2. In a theatrical counterweight system, means forming vertical parallel guides, a hopper mounted to move vertically upon the guides, a cross bar connected to the hopper, pulleys mounted upon the cross bar, a baton, an adjustable counter-balancing cable connected to the center of the baton and running over guide pulleys and downwardly and connected to the cross bar, a second equalizing cable connected at its ends to the ends of the baton and running over guide pulleys and around the pulleys upon the cross bar, a clamp upon the cross bar to engage and hold the cable in adjusted position, and means for adjusting the weight of the hopper to counter-balance the load carried by the baton. 3. In a theatrical counterweight system, means forming vertical parallel guides, a hopper mounted to move vertically upon the guides, a cross bar connected to the hopper, pulleys mounted upon the cross bar, a baton, an adjustable counter-balancing cable connected to the center of the baton and running over guide pulleys and downwardly and connected to the cross bar, a second equalizing cable connected at its ends to the ends of the baton and running over guide pulleys and around the pulleys upon the cross bar, a clamp upon the cross bar to engage and hold the cable in adjusted position, and means for adjusting the weight of the hopper to counter-balance the load carried by the baton.

pulleys and around the pulleys upon the cross bar, a clamp upon the cross bar to engage and hold the cable in adjusted position, 35 means for adjusting the weight of the hopper to counter-balance the load carried by the baton, a cable connected to the hopper and running over guide pulleys to be manually pulled to raise the hopper and lower 40 the baton, and a cable connected to the baton and running over guide pulleys to be manually pulled to raise the baton.

3. In a theatrical counterweight system, 45 means forming vertical parallel guides, a hopper mounted to move vertically upon the guides, a cross bar connected to the hopper, pulleys mounted upon the cross bar, a baton, an adjustable counter-balancing cable connected to the center of the baton and running over guide pulleys and downwardly and connected to the cross bar, a second equalizing cable connected at its ends to the ends of the baton and running over guide pulleys and around the pulleys upon the cross bar, a clamp upon the cross bar to engage and hold the cable in adjusted position, 50 and means for adjusting the weight of the hopper to counter-balance the load carried by the baton.

In testimony whereof I have signed my name to this specification.

ANTON MAZZANOVICH.
